(57) **CLAIM**

The ornamental design for a right angle attachment for rotary tool, as shown and described.

DESCRIPTION

FIG. 1 is a front right perspective view of the present new design for a right angle attachment for rotary tool;

FIG. 2 is a left elevational view thereof;

FIG. 3 is a right elevational view thereof;

FIG. 4 is a top plan view thereof;

FIG. 5 is a bottom plan view thereof;

FIG. 6 is front elevational view thereof; and,

FIG. 7 is a rear elevational view thereof.

The broken lines showing various features of a right angle attachment for rotary tool are for illustrative purposes only and form no part of the claimed design.
